UNITED STATES PATENT OFFICE

EMIL MUCKLE, OF WATERBURY, CONNECTICUT, ASSIGNOR TO WATERBURY CLOCK CO.,
OF WATERBURY, CONNECTICUT, A CORPORATION.

HAMMER-WIRE AND HUB THEREFOR FOR CLOCK-MOVEMENTS.

1,213,234.

Specification of Letters Patent. Patented Jan. 23, 1917.

Application filed August 30, 1916. Serial No. 117,645.

To all whom it may concern:

Be it known that I, EMIL MUCKLE, a citizen of the United States, residing at Waterbury, in the county of New Haven and State 5 of Connecticut, have invented a new and useful Improvement in Hammer-Wires and Hubs Therefor for Clock-Movements; and I do hereby declare the following, when taken in connection with the accompanying 10 drawings and the characters of reference marked thereon, to be a full, clear, and exact description of the same, and which said drawings constitute part of this application, and represent, in—

15 Figure 1 a view in elevation of a hammer-wire and hammer-hub constructed in accordance with my invention. Fig. 2 a broken edge view of the hammer-hub, showing the hammer-arm and hammer-tail of the hammer-wire broken away. Fig. 3 a detached view of the hammer-hub, and showing the angular locking-groove formed therein at one side of its center. Fig. 4 a broken view 20 of the hammer-wire showing the angular locking-bend formed therein for insertion into the corresponding locking-groove in the hammer-hub. Fig. 5 a detached edge view 25 of the hammer-hub showing its concentric staking-shoulder. Fig. 6 a detached plan view of the combined washer and cam-finger. 30

My invention relates to an improved hammer-wire and hammer-hub for use in clock-movements, the object being to provide simple, durable and reliable means for fastening the wire to the hub, whereby the hammer-arm and hammer-tail may be made in one piece and the danger of dislocation when made independent of each other and secured 35 in place by solder, avoided.

With these ends in view my invention consists in a hammer-wire and hammer-hub having certain details of construction as will be hereinafter described and pointed out in 40 the claims.

In carrying out my invention as herein shown, the hammer-hub 2 is formed in one of its faces with an angular locking-groove

3 arranged at one side of its central opening 4 which receives the stud (not shown) upon which the hub oscillates, the grooved face of the hub being formed with a concentric staking-shoulder 5. The hammer-arm 6 and hammer-tail 7 are formed in one piece with a triangular locking-bend 8 between them 50 corresponding in size and shape to the said locking-groove 3 in the face of the hub, the arm 6, tail 7, and bend 8 together forming 55 the hammer-wire. The parts having been constructed as described, the locking-bend 8 is inserted into the locking-groove 3 and secured in place therein against lateral displacement, by means of a flat washer 9 corresponding in diameter to the hub and having a central opening 10 fitting over the said 60 staking-shoulder 5 which is upset to hold the washer in place. As shown, the washer 9 is provided with a cam-like operating finger 11 for the operation of the hammer, 65 though this is not essential to my invention. 70

I claim:—

1. The combination with a hammer-hub having a central opening for the reception of the stud upon which it oscillates and also having a locking-groove formed in one of its 75 faces so as to clear the said opening, of a hammer-arm, hammer-tail and intermediate locking-bend made from one piece of wire, the said bend fitting into the said groove, and means for securing the bend of the wire 80 in the groove of the hub.

2. The combination with a hammer-hub having a central opening for the reception of the stud upon which it oscillates and also having a locking-groove formed in one of its 85 faces so as to clear the said opening, and also formed with a staking-shoulder concentric with such opening, of a one piece hammer-wire comprising a hammer-arm, a hammer-tail and an intermediate locking-bend adapted in shape to fit into the said 90 groove, and a washer applied to the grooved face of the hub over the said staking-shoulder by means of which it is secured in place.

EMIL MUCKLE.

Copies of this patent may be obtained for five cents each, by addressing the "Commissioner of Patents, Washington, D. C."
